UNITED STATES PATENT OFFICE.

CLAUD HENRY KLYNE, OF SHEERNESS, AND CHARLES JOHN BAKER, OF WESTMINSTER, LONDON, ENGLAND.

ELECTRIC INSULATION.

1,323,191.

Specification of Letters Patent. Patented Nov. 25, 1919.

Application filed May 12, 1917. Serial No. 168,204.

To all whom it may concern:

Be it known that we, CLAUD HENRY KLYNE, a subject of the King of Great Britain and Ireland, and a resident of Sheerness, Kent, England, (whose post-office address is 1 Naval Terrace, Sheerness, Kent, England,) and CHARLES JOHN BAKER, a subject of the King of Great Britain and Ireland, and a resident of London, (whose post-office address is 4 Broadway Chambers, Westminster, London, S. W.,) England, have invented new and useful Improved Electric Insulation, of which the following is a specification.

The present invention relates to the insulation of electrical apparatus and has special reference to the application of laminated insulating material such as mica. Mica has been considered a desirable insulating material for a long time owing to its good electrical insulating properties but its use has been limited owing to certain mechanical short-comings. Thus, while it can stand direct compression and shearing stresses it is not so good in resisting bending stresses and moreover it has a tendency to flake.

One object of the present invention is to bind sheet mica and similar insulating materials with metal sheet to prevent flaking, and at the same time to use the metal binding to take the stress of the means for securing the electrical apparatus to its base or support. This is best effected by passing securing bolts through the metal binding. For this purpose the binding can be extended at its center.

A further object of the invention is to secure the terminals or other metal parts of the apparatus to the mica. This may be effected directly, but it is found that a particularly stiff construction from a mechanical standpoint is secured if the binding along one edge of the sheet is employed for anchoring or supporting purposes and the binding along the other edge for securing the terminals or other metal parts of the apparatus. By this arrangement the invention employs mica sheets in the "edge on"

position, and this arrangement when employed in fuse and switch construction has the effect that when the switch is operated or the fuse detached the resultant stresses act substantially in the plane of the mica sheet.

Yet another object of the invention is to employ this so-called "edge on" construction with mica sheets in pairs to render the whole insulating construction a stiff box girder. The invention in all its embodiments has special value in that it enables large installations to be compactly built up of unit switches or fuses and the like.

Some embodiments of the present invention in its application to switch and fuse construction are shown in the annexed drawings, in which—

Figure 1 is a plan view of a knife switch in accordance with the invention.

Fig. 2 is a section of Fig. 1 on the line II—II.

Fig. 3 is a section on the line III—III.

Fig. 4 is a plan of a similar construction applied to a fuse block.

Fig. 5 is a cross section of Fig. 4 on the line V—V.

Fig. 6 is a cross section similar to Fig. 2, showing a slight modification.

Fig. 7 is a side view of a brush type of switch embodying the present invention.

Fig. 8 is a plan of the base of this switch with the operating mechanism removed.

Fig. 9 is a cross section of Fig. 8 on the line IX—IX.

Fig. 10 is a perspective view of the metal binding strips employed in Figs. 7 to 9.

Fig. 11 is a side view of a fuse base constructed in accordance with the invention.

Fig. 12 is a plan of same.

Fig. 13 is a cross section on the line XIII—XIII of Fig. 11.

Fig. 14 is a cross section on the line XIV—XIV of Fig. 11.

Fig. 15 is a perspective view from the inside of one of the plates of Figs. 11 to 14.

Figs. 16 and 17 are respectively side view and end view of a fuse fitting in accordance with the invention with the fuse in position.

Figs. 18 and 19 are similar views of a double plate fuse construction with the fuse removed.

Fig. 20 is a side view of a switch embodying the invention, and

Fig. 21 is a perspective view of one of the plates used in Fig. 20 viewed from the outside.

Referring first of all to Figs. 1 to 3, the 10 insulated base of the knife switch comprises a strip of mica 1 (shown for simplicity as a single sheet of natural thickness) with its long edges bound, so to speak, by strips of brass 2 bent to the necessary 15 shape. The strips of brass in their middle portion have extensions, the left hand one extending below the mica sheets and that on the right extending above as seen at 3 in Fig. 1. Bolts 4 passing through these brass extensions serve for securing the insulating base to the stout metal plate or strip 14 provided with holes for securing the switch in position. In such a construction as this it is not necessary for the ends of the sheets of 25 mica to be bound with metal, but it is found sufficient to secure the long sides of the layers. The fixing strip 14 can be of any length in order to accommodate any desired number of switch units side by side.

30 The metal contacts of the switch are shown at 5. They are secured to the mica itself by screws which pass through the latter. This provides quite a satisfactory construction owing to the capacity of mica for 35 resisting the tearing out of these screws. The switch blade 6 and the handle 7 are of known construction.

Figs. 4 and 5 show a fuse block which is very similar in construction to the above described switch. Corresponding reference characters are used for corresponding parts in the two devices. The metal terminals 51 of the fuse have extensions 8 for securing the circuit wires, and as the particular construction shown is designed for use in damp locations, at either end of the insulating base the brass binding strips are covered by a sheet of mica 9, with a spacing or backing piece of mica 10 between the covering sheet 50 9 and the base mica 1. The effect of this is merely to give a long leakage path to counteract the effect of the conductivity of moisture gathering on the insulating base. Fig. 6 shows a modification in which, in the 55 pressing the brass binding strips 2 are formed with a web to make them of so called "girder" section in order to withstand the bending stress to which they may be subjected more particularly in large

60 switches and the like. This construction has the further most important advantage that the upstanding ridges on the brass strip 2 serve as a protection for the mica sheet 9.

In Figs. 7 to 10, the invention is shown 65 applied to a brush type switch. The base is

best seen in Fig. 7. The layer of mica 1 has the brass binding strips 2 and at one end these are covered with a sheet of mica 9 for the purpose described in connection with Fig. 4. In this instance, however, instead of lapsing over the brass strips at their middle portion each of the strips at one end is bent at right angles to the base in order to form a pair of upstanding lugs or ears 11. These lugs are drilled at 13 to take the pivot 70 of the switch handle 7, which, in known manner, carries the bridge member of the switch and the brushes 16. In this construction there is also shown an insulating shield 15 between the lugs 11 and consisting of a 80 sheet of mica turned up at either side.

In the construction shown in Figs. 11 to 15 a pair of mica plates of desired thickness 1, 1^a, are used, the lower edges of each being bound by sheet metal 2, the configuration 85 of which can be best seen from Figs. 11 and 15. These lower binding strips serve to secure the compound plates to the supporting base (not shown). As seen in Fig. 15 on the inside of each strip a tongue 17 is cut away 90 and bent over; through each of these tongues a bolt 4 passes and serves to secure the device to the base.

In this particular construction the binding 95 of the upper edge is reduced to a minimum and consists of strips 18. On these strips the plates 19 are secured by means of screws, and on the plates 19 the fuse clips 20 are secured.

In this construction and in all constructions in which more than one unit of metal and mica is employed the complete structure forms the equivalent of a beam of box girder section. In Figs. 16 and 17, however, which show only a single compound sheet the construction is equivalent to an I girder. In this construction the lower edge of the mica sheet 1 is embraced by a riveted metal sheet 2, the configuration of which will be best seen in Fig. 16. Here again the binding 100 strips 18 of the upper edge are insignificant in comparison with the lower binding 2.

In connection with the shapes of these binding strips it should be pointed out that the rivets 21 are so disposed and the edges 115 of the strips so shaped that it is very difficult to choose a line of bending over the face of the compound sheet which shall pass over mica alone. If practically any straight line is drawn right through the 120 sheet it will be found to pass through a portion of metal, so that the resistance to bending of the whole device is increased in this way.

The plates 19 and the fuse clips 20 are 125 secured in substantially the same way as in the previous construction. In this case, however, the fuse 22 is shown in position.

This particular construction is specially designed so that a number of fuses can be 130

arranged in line side by side and it is intended that this construction be assembled by drilling the binding strips 2 and threading a number of these units upon a metal 5 supporting or assembling rod or rods 23.

The same remark applies to the next construction shown in Figs. 18 and 19, except that it is convenient here to mount the device on a pair of long supporting or assembling rods 24, 25. Thus, this construction otherwise is the same with that shown in Figs. 16 and 17 with the following two small exceptions: The configuration of the binding strips 2 and 18 is slightly different and 15 two mica sheets 1 and 1^a are employed.

In Figs. 20 and 21, a switch construction is illustrated. The two compound sheets of metal and mica are very similar to those shown in the fuse base of Figs. 18 and 19. 20 The switch itself is of a known type with a carbon break and need not be described in detail, except that it should be mentioned the switch handle is pivoted in upstanding brackets 31 which are formed from a metal 25 sheet continuous from the base and secured to the binding strip 2. This sheet 31 is secured to the strip 2 by screws 26 and to the base of the apparatus by screws 27, and therefore serves as a means for securing the 30 binding strip 2 to the base of the apparatus.

The invention is only illustrated in connection with switches and fuse blocks, but can be applied to mica or similar insulating 35 material when the latter is used for the insulation of other electrical apparatus. The outstanding advantage of the invention resides in the fact that the construction lends itself to the manufacture of units capable 40 of standardization and extremely easy to assemble in any numbers in any combination which may be required in practice.

What I claim is:—

1. In combination, a sheet of insulating 45 material of small mechanical strength, a strengthening metal binding surrounding an edge of said sheet, metal parts secured upon said sheet not in contact with said binding, and supporting means engaging 50 said binding.

2. In means for insulating electrical apparatus, the combination of a sheet of mica receiving the terminals of said apparatus, metal binding gripping the longitudinal 55 edges of said mica sheet, and anchoring bolts passing through said metal binding.

3. In combination, a strip of mica, metal parts fastened thereon and adapted to be subjected to mechanical forces and electrical 60 pressures, a support, and metal binding engaging said support, and folded around an

edge of said strip and extending into proximity to said metal parts, so as to transmit said mechanical forces to said support.

4. In combination, a strip of mica, metal 65 parts mounted upon one edge of said strip, and adapted to be subjected to mechanical stress chiefly in the plane of said strip, and metal binding surrounding an edge of said strip and adapted to resist flexure thereof. 70

5. In means for insulating electrical apparatus, the combination of a pair of parallel mica sheets, metal binding strips along the longitudinal edges thereof and means mechanically uniting each binding strip of 75 one sheet to the corresponding binding strip of the other so converting the whole into a box girder.

6. In combination, a sheet of mica, sheet metal strips engaging one edge thereof, 80 metal parts mounted upon said strips and adapted to be subjected to mechanical stress chiefly in the plane of the sheet, sheet metal engaging opposite edge of said sheet of mica, and supporting means engaging said 85 last mentioned sheet metal.

7. An installation of insulators for electrical circuits comprising a plurality of parallel sheets of insulating material, metal binding gripping the longitudinal edges of 90 said sheets and an assembling rod passing through corresponding parts of the metal binding of all the sheets.

8. In electrical apparatus the combination of a sheet of mica, and separate metal binding strips along opposite edges thereof, and 95 said strips being extended over the surface of said mica and having sinuous free edges intermeshing with but not touching each other.

9. In electrical apparatus the combination of two parallel sheets of mica, metal binding strips engaging the edges of said sheets of mica, and means uniting the binding strips of the two sheets into girder form. 105

10. As an electrical insulating support, an elongated strip of mica, separate metal bindings folded around opposite edges of said strip, and extensions on said bindings spreading over said sheet toward the opposite edge, the extensions from one edge intermeshing with but not touching the extensions from the other. 110

In testimony whereof we sign our names to this specification in the presence of two 115 subscribing witnesses.

CLAUDE HENRY KLYNE.
